UNITED STATES PATENT OFFICE.

JAMES E. STEPHENSON, OF ROCHESTER, NEW YORK, ASSIGNOR TO GENERAL RAILWAY SIGNAL COMPANY, OF ROCHESTER, NEW YORK.

SWITCH-LOCKING DEVICE FOR RAILROADS.

Application filed March 18, 1927. Serial No. 176,508.

This invention relates in general to a lock device and has more particular reference to lock means for use in connection with railway track switches.

5 In operating track switches, and more particularly in cases where the switch in question is outlying some distance from a signal tower, it is often times desirable to have the operation of the switch under the 10 joint control of a tower man, and of a switch man at the location of the switch. In such cases it is desirable that means of communication between the tower man and the switch man on the track be afforded, together with 15 various indicating means for advising the proper parties when certain operations have been initiated or completed or both.

With the above and other considerations in mind it is proposed in accordance with 20 this invention to provide a switch lock which carries into effect the above set forth considerations.

Further objects of this invention are, to increase the efficiency, decrease the cost of 25 production, and prolong the useful life, of device of the character in question.

Further objects, purposes, and characteristic features of this invention will appear as the description progresses, reference being 30 had to the accompanying drawings, showing, solely by way of illustration, one embodiment of the invention. In the drawings:

Fig. 1 is a sectional side elevation of a 35 device in accordance with the present invention;

Fig. 2 is a front elevation of part of the device, with the casing door open and portions broken away and in section to better 40 show the construction; and

Fig. 3 is a top plan view of a part of the device with portions broken away to more clearly show the structure.

Referring to the drawings two casings 1 45 and 2 are mounted one on top of the other, held together by bolts 3, and supported on a hollow post 4 connected at its base 5 to a foundation structure 6.

Passing through the base 5 is a switch 50 operating lever 7 having a hole 8 therein for receiving a lock bolt 9 adjustably connected at 10 to a rod 11 arranged to be reciprocated by means of a crank 12 to which it is connected. The crank 12 is operated 55 by shaft 13 to which it is connected by pin

14, the shaft being rocked through substantially 180° by means of a handle 15. In connection with this handle it should be explained, for a purpose to be later explained, that just before the handle reaches its 90° position, moving counter clockwise, from the position shown in Fig. 2, the lock bolt 9 just clears the rod 7, while when rotated to 180° in a counter clockwise direction, from its position as shown in Fig. 2, the lock bolt 60 9 is raised considerably above the rod 7. The casing 2, in which the structure just described is received, has a hinged cover 16, and carries an inwardly projecting rib 17 arranged as shown in Fig. 2 to be directly in the path of the handle 15 when the cover is closed, and this rib is so positioned as to permit closure of the cover only when the handle 15 occupies the position shown in Fig. 2, or in any position, 65 70 when moved counter clockwise, up to the referred to position of slightly less than 90° from the horizontal at which time the bolt 9 just clears the hole in the lever 7.

A counter weight 47, is attached to rod 11 80 and operates, when handle 15 is moved counter clockwise from its shown position to just before it reaches a vertical position, to bias the handle clockwise to lock the switch lever 7, and when handle 15 is moved further towards its 180° position to bias the handle counter clockwise to unlock the switch lever. Thus the handle 15 has the unlock position 85 shown in Fig. 2 in which it is biased to switch locking position, a switch unlocking 90 position in which it is biased to switch locking position, and a switch unlocking position in which it is biased to switch unlocking position.

Connected to the crank 12 so as to rotate 95 therewith is a segment 18 having a notched portion 19 engageable by a detent 20 to thus prevent rotation of the handle 15. Engaging the upper side of the detent 20 is an arm 21 which operates an indicator 22, through 100 crank means 23, between stops 24, the indicator thus showing whether the detent 20 is in raised or lowered position.

For raising and lowering the detent 20, a 105 rod 25 is connected thereto and passes into a casing 26 in which is preferably a rotor type motor controllable by an attendant in a distant signal tower, for example. Instead of a rotor type motor, any other desired form of motor or other driving means ca- 110

pable of distant control, can equally well be used and it has been thought unnecessary to illustrate in detail either the moving means or a circuit or control means running from the casing 26 to a distant signal tower.

The detent 20 is carried by an arm 27 pivoted at 28 and carrying a contact 29 which cooperates with a fixed contact 30, the contacts being so arranged as to be separated when the detent is raised. These contacts 29 and 30 are connected in an indicating circuit (not shown) running to the above referred to signal tower and are employed to indicate to the tower man, the 15 position of the detent 20.

The track switch man before being able to unlock the switch lever 7, must have the detent 20 in raised position, and to enable him to notify the tower man who has control 20 of the motive means in casing 26, there is provided a push button 31 which he can depress to close contacts 32 and 33 formed of normally separated spring arms, to thereby notify the tower man that it is desired to 25 have the detent 20 raised out of the path of the segment 18.

From Fig. 1 it will be noted that operation 30 of the handle 15 rotates the shaft 34 to thus operate contacts makers 35 to make and break circuits including contact members 36. The circuits controlled by the means just described can control various devices, one being an indicating means in the signal tower to notify the tower man that the lock 35 bolt 9 has been raised.

Also included in the casing 2 is a spring 40 pressed plunger 37, biased outwardly by a spring 38 bearing against a support frame 39, the plunger carrying a contact member 40, which, in the outer position of the plunger, closes a circuit including contacts 41 positioned at either side of the member 40. When the member 37 is pushed inwardly the 45 circuit through the contacts 41 is broken, and this circuit controls any desired source of power such as batteries or the like, employed in connection with throwing of the track switch, and is conveniently designated as a "power-off" switch. On referring to 50 Fig. 3 it will be seen that closure of the cover 16 will force the plunger 37 inwardly and thus effectually cut off power from the system.

In the upper casing 1 is a series of contacts 42 arranged to control any desired circuits in connection, for example, with signal means for interlocking arrangements for the track switch, and these contacts 42 are operated by a rod 43 which is rocked through 55 a crank 44 connected to a pull rod 45 mounted in a casing 2 and spring pressed inwardly by spring 46 to break connection at the contacts 42. This rod 45 cannot be operated until after the cover 16 of casing 2 60 is opened and hence the mechanism both in

casing 1 and casing 2 is subject to control of the cover of casing 2.

A conduit 48 connects to casing 2, for carrying various lead-in wires. The device just described is used in the following manner. 70 It is assumed that the switch operated by the lever 7 is positioned a considerable distance from a signal tower the rod 7 being furnished with a single hole 8 for locking the switch, for example, only in main line 75 position. If a train, passing along the main line is to turn out into a siding controlled by the track switch in question, the track brakeman opens the door of casing 2 and advises the tower man by pressing the button 31, 80 that it is desired to operate the switch to turn out position. The tower man, if conditions be proper, energizes the motor in casing 26 so as to raise the latch 20, and upon raising of such latch, the tower man receives an indication that this has been done, by means controlled through a circuit including the contacts 29 and 30. The switch man at the track then turns handle 15 through substantially 180° to thereby 85 unlock the member 7, and in turning the handle 15, a circuit controlled by the contacts 36 gives an indication to the tower man that the switch is unlocked. In passing, it should be noted that even though the tower man de-energizes the motor in casing 26 after he has received information that the switch is unlocked, the latch 20 will still be held in its upper position, thus holding the indicated arm 22 in its upper position, and 90 the latch 20 will not fall to its lower position until the handle 15 has been rocked back to within a few degrees of the position shown in Fig. 2. The track brakeman now throws the switch and then rocks the handle 15 in a 100 clockwise direction just past a vertical position so that the handle is biased by means of a counter-weight 47, to the locking position the bolt 9 being prevented from locking the switch lever 7, because the hole 8 is 105 not in registry with the bolt at this time. With the handle in the stated position the door 16 can be closed on the casing 2, the rib 17 just clearing the handle 15, after 110 which the train proceeds onto the siding. The rear track switchman can now operate 115 the track switch to main line position, whereupon, as soon as it has reached its final position, the hole 8 registers with the bolt 9, which descends to lock the switch in main 120 line position and restore the various parts to the position shown in the drawing.

If desired, the rib 17 can be extended to cover the entire 180° of possible movement of handle 15, in which case, the cover 16 cannot be closed on its casing 2, until after the track switch has been thrown to main line position, and the lock bolt 9, lowered into hole 8.

While the present invention has been de- 125

scribed rather specifically, it should be understood that this description has been given solely by way of example, and is not intended, in any manner whatsoever, in a 5 limiting sense. Obviously the invention can assume many physical forms, and is susceptible of various modifications, and it is intended to include in this invention all such forms and modifications as come within the 10 appended claims.

Having described my invention, I now claim:—

1. In a switch lock, a switch operating lever, a lock bolt for the lever, a first casing 15 containing, operating means for the bolt, a distant controlled detent for the operating means, distant communicating means adjacent the operating means, means for indicating at a distance, the operation of the 20 distant controlled detent, and control and indication circuits controlled by the operating means, a second casing connected to, and communicating with, the first casing, switch means in the second casing operable only 25 from within the first casing, and lockable doors on the casings.

2. In a switch lock, a first casing, a switch operating lever, a lock bolt for the lever, operating means for the bolt, a distant controlled detent for the operating means, a door on the first casing, a second casing 30 connected to the first casing, an electric switch in the second casing, an operating rod in the first casing accessible only when 35 the first casing door is open, and means

connecting the rod to the electric switch.

3. In a switch lock, a track switch operating lever, a bolt for locking the lever, a first casing, an operator for the bolt in the casing, said operator having a locking position, an unlocking position in which it is biased to locking position, and an unlocking position in which it is biased to unlocking position, a door on the casing, means to prevent closure of the door when the operator 40 is in its last named position, a closed second casing connected to, and communicating with, the first casing, switch means in the second casing, and means inside the first casing, for operating the said switch means. 45

4. In a track switch lock, a switch operating lever, a lock bolt for the lever, a first casing containing, a manual operator for the bolt, a detent for preventing operation of the operator, distance controlled electrical 55 means controllable by a tower man distant from the track switch for releasing the detent to permit manual operation of the switch, means at the switch for communicating with the tower man, tower indication 60 circuits controlled respectively by the said electrical means, and by the manual operator, a second casing connected to the first casing, electric switch means in the second casing, and means, accessible only when the 65 first casing is open, for operating the electric switch means.

In testimony whereof I affix my signature.

JAMES E. STEPHENSON.
